COMBINATION OTTOMAN AND CHAIR

Samuel G. Reichman, Flint, Mich.

Application May 26, 1950, Serial No. 164,510

10 Claims. (Cl. 155—152)

1

My invention relates to improvements in a combined ottoman or foot stool and chair.

My invention relates more particularly to furniture of this type capable of alternate use, that is, either as a footstool or ottoman, or when desired as a low chair which has a back rest associated therewith so that it may be used for viewing television or for similar purposes about the house.

The principal object of the invention is the provision of a construction for an ottoman or other article of furniture in which there is a back rest concealed within the body or base of the ottoman so that the ottoman may be used as a foot stool when desired, the said back rest being secured within the said base and so arranged that a part of the ottoman may be moved to uncover the interior of the base and the back rest moved out of the opening to erect position in a movement including at least a pivoting of the said back rest.

Another of the principal objects of the present invention is to provide a combined ottoman or footstool and chair construction wherein the housing or base of the footstool is provided with a compartment in which a back rest or support is contained, the back rest being secured to the base in such a manner that it may be moved from its position within the base to a supported position outside of the base, the seat of the ottoman being available for use under either circumstance.

A further object of the invention is the provision of a seat construction for the ottoman which enables the seat to be disposed out of the path of the back rest as the seat back rest is being moved from within the base to the erect position outside of the same or vice versa.

Still a further object of the invention is to provide an article of furniture of the character described in which the back rest normally is concealed within the base of the ottoman beneath the seat, and in which the seat is capable of being swung to a position to uncover the top of the ottoman, the back rest being pivotally secured within the base in such a manner that it can be pivoted out of the base to its erect position, after which the seat can be moved to recover the base.

Many other objects will occur to those skilled in the art to which this invention pertains it being pointed out that many novel constructional features of my device will be brought out in the description which follows. In order to facilitate a greater and more complete understanding of

2

the invention, and the manner of using the same, and in order to comply with the statutes relating to patents, I have illustrated herein certain embodiments of the invention which are preferred forms, but I desire to emphasize that a great many variations from the specific details thereof are capable of being made without departing from the scope of or violating the spirit of the invention. It is therefore desired to be limited in scope only by the language of the claims appended hereto interpreted in their broadest range of equivalents commensurate with the prior art relating to the subject matter hereof.

In the drawings, in which like or similar characters of reference denote the same or similar part throughout the several figures thereof—

Fig. 1 is a generally front perspective view of one form of construction of my combined ottoman and chair, showing the same when used as an ottoman or footstool;

Fig. 2 is a generally similar front perspective view thereof with the back rest in operative position, showing the same when used as a chair;

Fig. 3 is a side elevational view of the combined ottoman and chair generally viewing the unit from the left of Fig. 2, with the back rest shown in the retracted position in dotted lines;

Fig. 4 is a cross-sectional view taken generally on the line 4—4 of Fig. 3 with the seat being shown in a swung open position in dotted lines;

Fig. 5 is a fragmentary detailed sectional view showing the back supporting frame and associated parts, and is taken on the line 5—5 of Fig. 3.

I have shown in Fig. 1 an ottoman or footstool which may include generally the base 10 having the upholstered top 12 and suitable corner legs 14 to support the same upon the floor. The top 12 may be of the usual type provided with a rigid bottom wall 16 and suitable padding 18 covered by a leather or other flexible covering 20.

In the construction shown in Figs. 1 to 5 inclusive, the top is connected by a pair of hinges 22 and 24 to one of the side walls 26 of the base 10, it being provided at its opposite side with a spring latch member 30 which snaps over a stop 32 connected to the opposite side wall 34 of the base 10.

The base of the unit is preferably rectangular, having the side walls 26 and 34 previously mentioned, the front wall 36 and the back wall 38, the back wall 38 being provided with a pair of notches 40 and 42 for a purpose which presently will become apparent.

When it is desired to use the unit as a chair, 55 a back rest designated generally 44 which is

normally concealed within the base 10 may be swung to an erect position so that when the unit is used as a chair a seat and back rest are provided. The back rest may comprise a prop having a pair of tubular frame members 44 and 46 flattened at their lower ends as indicated at 45 and pivotally mounted upon pin members 48 and 50 secured in suitable blocks 52 and 54 respectively mounted adjacent the opposite side walls 26 and 34 within the base.

The free end of the back rest 11 is formed in the usual manner as such articles are constructed, with a padded member P against which the user's back is adapted to engage. The member P may be secured between the tubular frame members 44 and 46 in any suitable and well-known manner at the upper ends thereof as viewed in Fig. 3.

The flattened ends 45 of the tubular frame members 44 and 46 are identically offset from the main body of their respective member giving rise to the connecting angular bends 56. With the seat top 12 pivoted to a position illustrated in Fig. 4 in dotted lines, in which it uncovers the interior of the base 10, the back rest frame is free to be pivoted counterclockwise out of the base 10 from the dotted line position of Fig. 3 to its solid line position illustrated in said Fig. 3. This latter position is that in which the same properly can be utilized as a back rest. The movement accomplishing this maneuver brings the angular bends 56 into the notches 40 and 42 respectively which obviously are suitably aligned to receive the said bends. In the position thus far described the back rest 11 is supported by the wall 38 and the pivots 48 and 50, and thereby is prevented from continuing its counter-clockwise movement. In other words, the wall 38 serves as a stop and support for the back rest. If now the seat top 12 is returned to its normal horizontally disposed position covering the base 10, its rear end, i. e., the left hand end as viewed in Fig. 3, locks the back rest frame in erect position. The lower surface 16 engages the upper edge of the wall 38 of the base, closing off the upper open ends of the notches 40 and 42 and forming therewith the passageways through which the tubular frame members 44 and 46 extend out of the base in erect, supporting position.

From the above and foregoing description it will be seen that I have provided an article of furniture which consists of a combined footstool or ottoman and chair and in which the said article readily and quickly can be converted from the one to the other by the user. The said article is characterized by the provision of a back rest which is totally concealed in the base when the article is being used as an ottoman, but which is secured to and supported by the base and is capable of being quickly moved from its place of concealment to an erect and operative position.

The invention is further characterized in one form by a seat top which is capable of being moved off the top of the base of the article of furniture, to permit the back rest to be pivoted out of the base through the top thereof, after which the seat top is returned to normal position. Replacing the back rest within the seat is a simple reverse procedure.

It is believed that the invention, its mode of construction and assembly, and its advantages readily should be understood from the foregoing without further description, and it should be manifest to those skilled in the art that I have

made a substantial and highly beneficial advance in the arts and sciences, the exact nature of which is set forth in the claims which follow.

Having thus described my invention, what I claim as new and desire to protect by Letters Patent of the United States is:

1. A combined ottoman and chair comprising a base having a top hingedly connected thereto at one side of the same, a back rest, pivot means within the base connecting the back rest to the base for movement of the back rest from a position totally within the base to a position extending erect from the base and clear of the top when the latter is in closed position upon the base, said back rest and base having formations arranged to cooperate to prevent movement of the back rest beyond said second mentioned position, and said top arranged to overlie said formations when in closed position to conceal the same.

2. A combined ottoman and chair comprising a hollow base having a seat top hingedly connected thereto at one side thereof and completely covering the base, a back rest, pivot means within the base and connecting the back rest on the interior of the base for swinging movement from a position concealed within the base upwardly to a vertical position, said back rest comprising a pair of arms having a back-supporting member attached to the ends of the arms, the said base having a back wall, and the said arms having shoulders adapted to engage on the top of the back wall when the back rest is in said vertical position to support the said back rest, and said seat top completely covering said base when said back rest is in concealed or vertical positions.

3. A unit of the type described comprising a box-like base having side walls, a cover member hingedly connected adjacent the top to one of the side walls of said base, a back rest including a frame having parallel arms pivotally connected on the interior of said base for swinging movement to raised position after said top has been swung open, said back rest being locked in position for use when said top is returned to normal position, parallel slots in said back wall for receiving said arms when said back rest is in raised position to permit the cover member to be returned to said normal closed position.

4. A combined ottoman and chair comprising a hollow base having at least a rigid end, a seat horizontally mounted thereon and completely covering same, a back rest generally horizontally arranged within the base and normally concealed therein, hinged means connecting the back rest on the interior of the base for swinging movement thereof from said horizontal arrangement projecting out of the base in at least a pivotal movement thereof to carry the said back rest to proper erect position for use by the occupant of the seat, means mounting the seat for movement to uncover the base to permit said swinging movement of the back rest, the bottom of the back rest engaging the upper edge of said rigid end for support thereof but only when in said erect position and having means formed thereon adapted to engage on said rigid end, said seat and rigid end having cooperating means to enable the seat to be returned to horizontal position upon the base.

5. A combined ottoman and chair comprising a box-like base member having side walls and a back wall, a cover member hingedly connected to one of the side walls of said base adjacent the top thereof, a back rest including a frame having elongate parallel arms, pivot means within the

base member connecting said arms at their lower ends to the base member on the interior thereof for pivotal upward movement of the back rest from a position totally within said base member to a vertical position on said back wall, the said arms having means integrally formed therewith adapted to engage the upper edge of said back wall when the back rest is in said vertical position to support the back rest on the back wall.

6. A combined ottoman and chair comprising a box-like base member having side walls and a back wall, a cover member hingedly connected to one of the side walls of said base adjacent the top thereof, a back rest including a frame having elongate parallel arms, pivot means within the base member connecting said arms at their lower ends to the base member on the interior thereof for pivotal upward movement of the back rest from a position totally within said base member to a vertical position astride said back wall and said arms having shoulder means integrally formed therewith adapted to engage the upper edge of said back wall when the back rest is in said vertical position to support the back rest on the back wall comprising a bend in each arm in proximity to its said lower end.

7. A combined ottoman and chair comprising a box-like base member having side walls and a back wall, a cover member hingedly connected to one of the side walls of said base adjacent the top thereof, a back rest including a frame having elongate parallel arms, pivot means within the base member connecting said arms at their lower ends to the base member on the interior thereof for pivotal upward movement of the back rest from a generally horizontal position totally within said base member to a vertical position astride said back wall, the said arms having means integrally formed therewith adapted to engage the upper edge of said back wall when the back rest is in said vertical position to support the back rest on the back wall comprising a bend in each arm in proximity to its said lower end thereby providing a shoulder portion adapted to engage said upper edge, said upper edge having a pair of recesses adapted to receive the respective bends of the arms, said cover member adapted to be returned to normal position when the said back rest is in vertical position with a free edge of the cover member engaged over said bends.

8. A combined ottoman and chair comprising a box-like base member having side walls and a back wall, a cover member hingedly connected to one of the side walls of said base adjacent the top thereof, a back rest including a frame having elongate parallel arms, pivot means within the base member connecting said arms at their lower ends to the base member on the interior thereof for pivotal upward movement of the back rest from a generally horizontal position totally within said base member to a vertical position astride said back wall, the said arms having means integrally formed therewith adapted to engage the upper edge of said back wall when the back rest is in said vertical position to support the back rest on the back wall, comprising a right angle bend in each arm, a pair of notches in the upper edge of the back wall to receive the bends, said cover member locking the bends in the notches

when said cover member is returned to its normal position.

9. A combined ottoman and chair comprising a box-like base having side walls, a cover member adapted to seat a person hingedly secured to the base and completely covering the same and adapted to be pivoted off the base to expose the interior thereof, a normally concealed back rest member comprising a back rest pad and an elongate frame, the back rest pad being secured on one end of the frame, pivot means on the interior of the base connecting the opposite end of the frame to the base for swinging movement of the entire back rest member between an erect position with all but the opposite end outside of the base and a generally horizontal position with the entire back rest member within the base, the frame having an angular bend therein forming shoulder means adapted to engage an upper edge of the base when said back rest member is in erect position, and said bend substantially offsetting the back rest pad from the pivotally connected end of the frame to permit the cover member to be returned to complete coverage of the base when the back rest member is in its erect position.

10. A combined ottoman and chair which comprises, a hollow base having generally vertically arranged side walls and a seat hingedly secured to the same and completely covering the base while resting upon the upper edges thereof, a back rest normally concealed within the base and adapted to swing between a horizontal position inside of the base to a vertical position substantially outside of the base to be used by an occupant of the seat when the seat has been swung open to uncover said base, the seat being adapted to be returned to covering position with the back rest in vertical position, said back rest comprising an elongate member having an offsetting angular formation between the ends thereof, one end having a back supporting portion, pivotal means connecting the opposite end of the elongate member on the interior of the base adjacent a side wall spaced below the said upper edges of said base with the formation arranged such that the elongate member when in vertical position extends from said pivotal means upward and parallel with a side wall, thence at an angle horizontally and outwardly of the base and said last mentioned side wall and beyond the extent of said seat when in covering position, and thence upwardly to said one end.
